ATTORNEY

UNITED STATES PATENT OFFICE.

VINCENZO BOSCHETTI, OF WEST NEW YORK, NEW JERSEY.

ELECTRIC WATER HEATER.

Application filed December 14, 1927, Serial No. 240,014, and in Italy March 5, 1927.

The present invention relates to an electric water heater of the type in which the water itself serves as a conductor and resistance for the current which heats it, the 5 water flowing in a relatively restricted space between two large surfaced electric terminals.

An object of the invention is to provide a heater of this character in the nature of a small compact unit which may be conveniently attached to any pipe line or faucet, and 10 which will serve to highly heat cold water flowing from the faucet or cold water passing through a pipe line.

Other objects of the invention are to provide 15 an electric water heater of simple, practical construction, which will be rugged, durable and efficient in use, and well suited to the requirements of economical manufacture and convenient installation.

With the above noted and other objects 20 in view, the invention consists in certain novel features of construction and combinations and arrangements of parts, as will be more fully hereinafter set forth and pointed out in 25 the claims. The invention may be more fully understood from the following description in connection with the accompanying drawings, wherein—

Fig. 1 is a side elevational view of a water 30 heater embodying the present invention.

Fig. 2 is a longitudinal sectional view there- 35 through.

Fig. 3 is a view similar to Fig. 2, but illustrating a slight modification.

Fig. 4 is a transverse sectional view taken 40 approximately on the line 4—4 of Fig. 2.

In the drawings I have used the reference 45 numeral 10 to designate a generally cylindrical block of conductive material which constitutes one terminal of the heater and which is arranged in a cylindrical shell 11 constituting the other terminal. The shell is spaced from all walls of the block 10 and cooperates therewith to define an annular water heating chamber 12 in which a thin film of water is always maintained and heated by the alternating current flowing through the water between the terminals 10 and 11.

The block 10 is provided at one end with 50 an upstanding neck portion 13 having a water passage 14 therein, which passage delivers into the annular chamber 12 through a plurality of relatively small radially disposed passageways 15.

In order that the block 10 may be conveniently mounted within the shell 11, one end

of the shell is formed as a removable cap 16 having threaded connection with the shell 11, and having a central opening 17 therein through which the neck 13 passes. The opening is of considerably larger diameter than the neck 13 in order that the neck may be insulated from the cap. An insulating ring 18 encircles the neck and is secured to the top of the cap 16. The terminal of an electric 60 wire 19 is clamped between the ring 18 and a washer 20 screwed on to the threaded upper end of the neck 13; the washer being held firmly in position by a nut or coupling member 21 screwed on to the top of the neck and 65 having a threaded socket 22 therein for attachment to the end of a pipe (not shown) which may deliver water into the passage- 70 way 14.

The lead wire 23 to the shell may be conveniently secured by a binding post or similar attachment 24 screwed directly into the interior of the shell at any desired point. The lower end of the shell is provided with a restricted outlet orifice 25 through which the 75 heated water escapes.

In Fig. 3 I have illustrated a slight modification of the device entirely similar to the form shown in Figs. 1 and 2, except that the restricted orifice 25 is surrounded by a nipple 80 26 to which is connected a coupling member 27 similar to the member 21. This form of the invention is designed for use where the heater is to be employed in a pipe line while the form illustrated in Figs. 1 and 2 is more 85 suitable for direct attachment to a faucet or the like.

It is understood that the lead wires 19 and 23 are connected to opposite sides of any 90 suitable source of alternating current.

When no water is present in the shell 11, the air in the shell will serve to insulate it from the block 10 and prevent any current flow. When water is permitted to enter the shell however, through the passageways 14 100 and 15, the water is sufficiently conductive to permit current flow between the members 10 and 11, and sufficiently electrically resistant to become highly heated in its passage through the shell.

Obviously, various changes and alterations 105 might be made in the general form and arrangement of the parts described without departing from the invention. Hence I do not wish to limit myself to the details set forth, 110 but shall consider myself at liberty to make such changes and alterations as fairly fall

within the spirit and scope of the appended claims.

I claim:

1. An electrical hot water heater including a cylindrical shell having a water outlet at one end, a cylindrical block housed within the shell and insulated therefrom, said block extending from said shell to provide a coupling means for said heater, said block and shell cooperatively defining an annular water heating chamber between them closed at the end opposite the outlet of the shell, and means for introducing water directly into the chamber. 5
2. An electrical hot water heater including a cylindrical shell having a water outlet at its lower end, a cylindrical block housed within the shell and insulated therefrom, said block extending from said shell to provide a coupling means for said heater, said block and shell cooperatively defining an annular water heating chamber between them closed at its upper end, and means for introducing water directly into the upper end of the chamber, said means comprising passageways in the block. 10
3. An electrical hot water heater including a cylindrical shell having a water outlet at its lower end, a cylindrical block housed within the shell and insulated therefrom, said block extending from said shell to provide a coupling means for said heater, said block and shell cooperatively defining an annular water heating chamber between them closed at its upper end, and means for introducing water into the chamber, said means comprising radial passageways in the block, said block having a neck projecting through an opening in the shell and bored to define a water inlet passageway leading to the radial passageways. 15
4. An electrical hot water heater including a cylindrical shell having a water outlet at its upper end, a cylindrical solid block housed within the shell and insulated therefrom, said block extending from said shell to provide a coupling means for said heater, said block and shell cooperatively defining an annular water heating chamber between them closed at its upper end, and means for introducing water into the chamber, said means comprising radial passageways in the upper end of the block, said block having a neck projecting through an opening in the shell and bored to define a water inlet passageway leading to the radial passageways, which lead to the annular chamber. 20
5. An electrical hot water heater including a cylindrical shell having a water outlet at one end, a cylindrical block housed within the shell and insulated therefrom, said block and shell cooperatively defining an annular water heating chamber between them, means for introducing water into the chamber, means for connecting said block and shell to opposite sides of a source of alternating current, said means including an exterior binding post on the shell, and a threaded neck on the block projecting through an opening in the shell and serving as a binding post. 25
6. An electrical hot water heater including a cylindrical shell having a water outlet at one end, a cylindrical block housed within the shell and insulated therefrom, said block and shell cooperatively defining an annular water heating chamber between them, means for introducing water into the chamber, means for connecting said block and shell to opposite sides of a source of alternating current, said means including an exterior binding post on the shell, and a threaded neck on the block projecting through an opening in the shell and serving as a binding post, the last mentioned shell opening being formed in a removable cap constituting one end of the shell. 30
7. An electrical hot water heater, comprising a shell having an outlet in its bottom, an apertured cap on the upper end of the shell, a block in the shell and spaced therefrom to form a water chamber, said block having radial passages in its upper end and provided with a neck projecting through the cap and having a passageway leading to the radial passages, means for securing the terminal of an electrical wire on the neck of the block, and means for securing a second electrical wire to the outer face of the shell. 35

Signed at New York, in the county of New York and State of New York, this 12th day of December, A. D. 1927.

VINCENZO BOSCHETTI.
